UNITED STATES PATENT OFFICE

JOSEPH ROBINSON, OF NEW YORK, N. Y.

AUTOMATIC TRAIN PIPE COUPLING

Application filed May 4, 1926. Serial No. 106,718.

My invention relates to automatic train pipe couplings, and more particularly to brackets, or universal supports, for such couplings. Among its objects are to provide an improved means for permitting universal movement to the coupling head, the means including especially an improved bracket which is inexpensive to make, simple, strong, and efficient.

10 The invention resides in the combinations, arrangements and improvements hereinafter described, pointed out in the appended claims, and illustrated in the accompanying drawings in which

15 Figure 1 is a sectional side elevation of my improvement.

Figure 2 is a front elevation of the bracket shown in Figure 1. In this view the member B is shown in section, and the tie rod 20 is 20 omitted.

25 Figure 3 is a horizontal sectional view through the center of the anchor device or lower end A of the bracket. In this view the forward end of the tie rod 20 is shown in elevation.

Figure 4 is a section through the lower ends of the halves 5 and the upper portion of the anchor device A taken on substantially the line 4—4 of Figure 1.

30 My improved bracket comprises halves 5 and an anchor device A. The halves are preferably formed of wrought iron by shearing them from a flat bar having the width and thickness of the upper end of the halves, 35 though they may of course be otherwise formed if desired. The halves span a lug 6 suitably secured to a car coupler (not shown) and are bolted to the lug by bolts 7. From a point approximately mid-way their 40 length the halves flare rearwardly as shown especially in Figure 1. An anchor device A, is arranged to form the lower portion of the bracket. This anchor device is provided with a vertically extending flat per-

45 forated lug or portion 9. The lug 9 lies

between the lower ends of the halves 5 and is rigidly secured thereto by a rivet 10, which extends transversely through the halves 5 and the lug 9 near the lower end of the halves, and by tongues 11 and 12 which are formed integral with the lug 9 and which are turned laterally across the front face of the lower end of the halves 5 as shown particularly in Figures 2 and 4. This arrangement produces a very effective means for locking or tying 55 the anchor device A to the halves 5.

A hollow head supporting member B such as shown in my co-pending application Serial No. 364,920 filed March 11th, 1920, for improvements in automatic train pipe connectors, spans the lower end or anchor device A of my improved bracket. The supporting member comprises spaced straps or sides 14 which lie on opposite sides of the central vertical portion 15 of the anchor device, and these straps are flared at their rear ends, as at 16, Figure 1, to bear against the laterally extending shoulders 17 and 18 of the anchor device, when the automatic connector is in the uncoupled position, thereby properly 60 positioning the pipe or member B and coupling head (not shown). The rear end of the member B is provided with a vertically extending flange 19 with which the straps 14 are integral, and this flange is perforated 65 as shown and normally bears against the rear side of the anchor device A. A tie rod 20 having a perforated elongated forward end, see Figure 3, extends through the perforation in the flange 19 and around the middle portion 70 of the anchor device, upon the front face of which portion the tie rod is seated for free universal movement. The opening in the tie rod is large enough to permit it to be passed 75 upwardly over the projections 17 of the anchor device, and at their point of contact the tie rod and the anchor device are round in cross section, and hence flare in opposite directions, as shown in Figures 1 and 3. Between the flange 19, and a suitable adjustable 80

90

abutment 21 mounted on the rear end of the tie rod, a coil buffer spring 22 is seated. The spring surrounds the tie rod and is normally under sufficient compression to yieldingly maintain the member B in the desired horizontal coupling position with the flange 19 bearing against the rear side of my improved bracket. The member B is suitably connected to any desired form of coupling head. 10 In the drawings no coupling head is illustrated but a satisfactory type is shown in my aforesaid co-pending application.

In addition to properly positioning the member B, the flared portions 16 of the straps 15 14 prevent undue rotation of the coupling head when in the normal uncoupled position, such prevention being accomplished by contact of these portions 16 with the laterally extending or over hanging shoulders 17 and 20 18 of the anchor device A. When the coupling head moves to the coupled position the flange 19 moves rearwardly out of contact with the anchor device, and when in this position the coupling head and member B have 25 limited rotary movement with respect to the bracket. When in this position they also have, by reason of the resiliency of the buffer spring 22 and the large opening through the flange 19, limited vertical and lateral movement 30 independent of movement of the tie rod 20.

What I claim is:

1. An automatic train pipe coupling comprising in combination, a hollow member 35 adapted to support a coupling head, a tie rod extending into said hollow member through the rear end of the latter, and a bracket extending from above said member downwardly into the hollow thereof and 40 through the forward end of said tie rod, said bracket comprising halves between the lower ends of which a vertically disposed anchor device is securely locked, said device being provided with laterally extending shoulders 45 for supporting said member.

2. An automatic train pipe coupling comprising in combination, a bracket, a head supporting member spanning the lower end of said bracket, said member being provided at 50 its rear end with a perforated projection, a tie rod extending through said projection and embracing the lower end of said bracket and mounted on the front face thereof for rocking movement, the lower end of said bracket comprising a separately formed vertically disposed anchor device having transversely extending portions which prevent dislodgment of said member from the bracket, and a spring surrounding said tie rod at the rear of the bracket to yieldingly support said member and said coupling head. 55

3. A bracket for an automatic train pipe coupling head comprising in combination, a pair of vertically disposed halves bolted to a 60 lug on a car coupler, an anchor device car-

ried at the lower end of said halves and provided with portions turned across the faces of said halves to lock the anchor device thereto, said anchor device having on its front face a seat into which a tie rod is adapted to 70 be hooked.

4. An automatic train pipe coupling bracket comprising in combination, vertically disposed halves suitably secured to a car coupler lug, an anchor device substantially 75 I-shaped in front view rigidly secured to the lower end of said halves, said anchor device having a lug extending vertically upwardly between the lower end of said halves, and means for locking the anchor device to said halves, said means comprising a locking element extending transversely through the halves and said lug on the anchor device, and having a portion integral with the last named lug and turned across the front face 85 of one of said halves.

5. An automatic train pipe connector bracket comprising in combination, a vertically extending member secured to a car coupler lug, an anchor device tied to the 90 lower end of said member by means including a portion of the anchor device turned across the face of the member, transversely extending portions on the lower end of said anchor device, and a tie rod seat lying between said portions and the lower end of said member.

6. A bracket for automatic train pipe couplers, comprising in combination, an upper member provided with spaced portions, an 100 anchor device secured to said upper member and having a lug rigidly secured between said spaced portions, said anchor device having on its front face a seat for a tie rod and also having laterally extending portions for engaging a head-supporting member. 105

7. A bracket for automatic train pipe couplers, comprising in combination, an upper member provided with spaced portions, an anchor device secured to said upper member 110 and having a lug rigidly secured between said spaced portions, said device also having two portions thereon which are bent in opposite directions across the face of said upper member, said anchor device having on its front face a seat for a tie rod and also having laterally extending portions for engaging a head supporting member. 115

8. A bracket for automatic train pipe couplers, comprising in combination, an upper 120 member and an anchor device formed separately from and rigidly secured to said upper member, said device having two portions thereon which are bent in opposite directions across the face of said upper member, said anchor device also having on its front face a seat for a tie rod and having laterally extending portions for engaging a head supporting member. 125

9. An automatic train pipe coupling, com- 130

prising in combination, a hollow member adapted to support a coupling head, a tie rod extending into said hollow member through the rear end of the latter, and a bracket extending from above said member downwardly into the hollow thereof and through the forward end of said tie rod, said bracket comprising an upper member and a vertically disposed anchor device formed separately from and secured to the lower end thereof, said device being provided with laterally extending shoulders for engaging said supporting member.

In testimony whereof I hereunto affix my
15 signature.

JOSEPH ROBINSON.
